UNITED STATES PATENT OFFICE

JOSEPH C. BABST AND JAMES H. FISCH, OF BARNESVILLE, AND JOSEPH BAUER, OF ST. PAUL, MINNESOTA

ICE SAWING MACHINE

Application filed June 27, 1930. Serial No. 464,398.

This invention relates to a machine for sawing ice, one of its objects being to provide a self-propelled machine the saw of which is supported in a novel manner and has an adjustable gauge for regulating the depth of the cut produced.

A further object is to drive the saw by means of novel power transmitting mechanism which includes a differential whereby uniform or equalized power is transmitted to both ends of the shaft on which the saw is mounted.

Another object is to provide novel means for propelling the machine along the surface of the ice being cut, the speed being constantly under control of the operator and there being a means whereby the ice engaging or propelling element can be quickly forced into or lifted from engagement with

the supporting surface.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings

Figure 1 is a side elevation of the machine.

Figure 2 is a bottom plan view.

Figure 3 is a vertical longitudinal section of the machine, the motor hood being shown in elevation.

Figure 4 is a section on line 4-4, Figure 1, the differential housing being shown in elevation.

Figure 5 is an enlarged section through the differential, said section being taken on the line 5-5, Figure 4.

Figure 6 is a section on line 6-6, Figure 3.

Figure 7 is a view partly in elevation and partly in section of a portion of the controlling mechanism for the propelling wheels.

Referring to the figures by characters of

reference, 1 designates the runners of a sled structure, each of these runners having its lower surface slightly bowed in the direction of its length so that the sled can rock slightly on a supporting surface and it thus becomes possible readily to turn the machine.

The sled structure includes side frame members 2 on the back portions of which is mounted an internal combustion engine housed preferably in a hood as shown at 3. This engine is of the automobile type and its drive shaft 4 is provided with a gear 5 located in a differential housing 6.

Extending transversely within the housing 6 is a transmission shaft 7 one end of which is engaged by a screw 10 whereby the shaft can be shifted longitudinally to compensate for wear. This screw is mounted as herein-after explained.

A friction disk 11 is secured to that end of shaft 7 remote from the screw 10 and this disk has a central recess as shown at 12.

Bearings 13 are provided on the outer side of one of the frame members 2 and journaled in the bearings is a shaft 14 on which a sleeve 15 is slidably mounted. This sleeve is feathered on shaft 14 as shown at 16 and carries a friction disk 17 which, when in neutral position, is disposed opposite the center of disk 11 where it will not contact therewith because of the recess 12.

Sleeve 15 rotates within a collar 18 which is connected by a rod 19 to a shifting lever 20. Thus by means of this lever sleeve 15 can be moved along shaft 14 to bring the friction wheel 17 to any desired position relative to the disk 11 so as to rotate shaft 14 in either direction at any speed desired. The parts can be held in the position to which they have been moved by means of a toothed segment 21 having the usual pawl mechanism 22 for engagement therewith to lock the lever 20.

Shaft 14 has a gear 23 which meshes with another gear 24 secured to a transverse shaft 25. These gears may be located in a protecting housing 26.

Mounted to swing on the shaft 25 between the runners 1 is a frame 27 which can be suitably braced as shown in Figure 2. This frame

is extended forwardly from the shaft 25 and carries at its free end, a transverse axle 28 mounted for rotation. To this axle are secured wheels 29 having teeth radiating therefrom as shown at 30. A sprocket 31 is secured to the axle and is adapted to receive motion from the sprocket 33 on the shaft 25 through a chain 32.

The teeth 30 will be held by pressure normally in engagement with the surface supporting the machine, and it will be obvious that when the teeth are thus located motion transmitted to the wheels 29 through the mechanism already described will cause the machine to move either forwardly or backwardly at any desired speed.

For the purpose of controlling the engagement by the teeth 30 with the supporting surface a transverse rock shaft 34 is used. This rock shaft has a crank arm 35 adjacent to each of the runners 1 and links 36 connect these arms to the frame 27.

Another crank arm 37 is extended from the shaft 34 at one end thereof and to this arm is attached one end of a spring 38. The other end of the spring is adjustably connected by a chain 39 or the like to a bracket 40.

It will be apparent that by providing spring 38 the teeth 30 will be forced yielding into engagement with the surface of the ice, it being possible readily to regulate the pressure by placing the spring 38 under increased or reduced tension.

Another crank arm 41 is connected to the shaft 34 and to this arm is pivotally connected a controlling rod 42 which is slidably mounted in a bracket 43 provided with an opening 44 for the reception of the rod. A tooth 45 projects from the rod and is so located that when shaft 34 is rotated to lift the teeth 30 out of engagement with the ice, this tooth will drop into engagement with the lower wall of the opening 44 as shown particularly in Figure 7.

For the purpose of bringing the rod 42 to the position shown in Figure 7 a link 46 connects the rod to one arm of a bell crank 47 fulcrumed on the sled structure. The other arm of the bell crank forms a pedal 48 which, when depressed, will cause the bell crank to pull through link 46 and cause the rod 42 to lift wheels 29 against the action of the spring 38 and bring the tooth 45 to holding position.

For the purpose of releasing the wheels a small tripping lever is pivotally connected to the rod 42, this lever being indicated at 49. The lever is extended through the opening 44 and bears downwardly on the lower wall thereof at a point between the fulcrum 50 of the lever and the free end thereof. Thus when the free end is pushed downwardly it will rock on the lower wall of opening 44 and cause tooth 45 to be lifted out of engagement with the bracket 43. Consequently spring

38 will be released and the mechanism will be promptly shifted to bring the teeth 30 into engagement with the ice.

The gear 5 in the differential housing 6 meshes with a ring gear 51 with which rotates a series of radially disposed intermediate gears 52. These gears, in turn, mesh with opposed bevelled gears 53 and 54 and are carried by an intermediate collar 55 which is feathered on the shaft 7 as indicated at 56. Gear 53 is keyed to one end of a tubular shaft 57 which is mounted for rotation on shaft 7 while gear 54 is keyed or otherwise secured to a tubular shaft 58 also mounted for rotation on shaft 7. The collar 55 is interposed between these tubular shafts.

One end of shaft 57 is closed and the screw 10 is mounted in a threaded opening 9 in said end.

It will be apparent that the differential gearing which has been described operates in the same way as any ordinary gearing of this type. Rotation of the gear 51 causes shaft 7 to rotate and motion will be transmitted through the gears 52 to the gears 53 as said before, so that tubular shafts 57 and 58 will also be driven but can operate at different speeds.

The tubular shafts 57 and 58 are journaled in tubular extensions 59 of the differential housing 6 and to the shaft 57 is secured a sprocket 60 while another sprocket 61 is secured to the tubular shaft 58.

Angle arms 62 are mounted at one end on the tubular extension 59 and extend along opposite sides of an arcuate hood 63 formed of sheet metal and welded or otherwise suitably connected to the arms. These arms, with their flanges extending laterally away from the hood, as shown particularly in Figure 6, constitute reinforcements for the hood so that it can be made of sheet metal but will be light and rigid. Journaled in the arms at a point concentric with the arcuate wall of the hood is a saw shaft 64 and secured to this shaft so as to extend upwardly into the hood 63 is an ice saw 65 of the circular type. A sprocket 66 is secured to each end portion of the shaft 64 and these sprockets are engaged by chains 67 receiving motion from the respective sprockets 60 and 61. Thus it will be seen that power will be applied equally to both ends of the shaft 64 through the differential.

For the purpose of limiting the downward movement of the saw a gauge 68 is employed. This consists of side strips 69 pivotally connected as at 70 to the sides of the hood 63 and merging at their forward ends along curved lines into upwardly extended arcuate arms 71. The side strips can be secured by bolts 72 or the like to fingers 73 extending from the front end of the hood. These bolts are adapted to be inserted through any of the

apertures 74 provided in the arms 71. Thus it will be seen that the gauge will contact with the surface of the ice and limit the depth of the cut produced by the saw.

- 5 For the purpose of preventing ice chips from being projected forwardly an undesirable distance from the machine during the sawing operation a flap can be suspended between the fingers 73 and between the arms 71. The lower end of the flap can ride along the surface of the ice and the forwardly projected ice chips will strike the flap and be deflected thereby downwardly onto the surface of the ice instead of being projected forwardly and causing discomfort to persons walking in front of the machine.

10 For the purpose of raising and lowering the hood 63 and the saw 65 a yoke 76 is pivotally connected to the top of hood 63 while its upper end is pivotally connected to the upper portion of a lever 77 fulcrumed at 78 upon the side members 2 of the machine. A link 79 connects the upper portion of lever 77 to a lever 80 which is fulcrumed at its lower end on one of the members 2 of the machine as shown at 81. This lever carries a pawl mechanism 82 of the usual type adapted to engage a notched segment 83 so as to be held in one extreme position with the saw and hood elevated above the surface of the ice. There is nothing to limit the movement of lever 80 to the right in Figure 1 except the gauge 68 contacting with the ice.

15 The machine may be provided with guiding attachments extending from the sides thereof. Each of these attachments can include a rod 84 slidably and rotatably mounted in brackets 85 and having a spring 86 for holding the rod normally pressed downwardly. An arm 87 is extended from the lower portion of rod 84 and has a blade 88 adjustably mounted thereon. This blade is adapted to travel in the cut previously produced by the machine and will, obviously, keep the machine parallel with said cut as it travels over the ice. A brace 89 can be pivotally connected to the outer ends of the arm 87 and can be detachably mounted on a lug 90 extending from the side of the frame.

20 When it is desired to raise the gauge or guide blade 88 it is merely necessary to lift on a lever 91 which is connected by a chain 92 or the like to the lower portion of rod 84.

25 When the guide or gauge blade 88 is not to be used, the brace 89 can be disconnected from lug 90 and from the arm 87 and said arm can be then swung laterally against the side of the machine as shown at the lower portion of Figure 2.

30 Handles 93 can be extended backwardly from the machine for use when it is desired to turn the machine after the saw and other parts have been disengaged from the ice cut.

35 What is claimed is:

- 65 1. An ice sawing machine including a sled

structure, ice sawing mechanism carried by said structure, toothed propelling wheels, yielding means for holding the wheels normally in engagement with a supporting surface, foot actuated means for disengaging said wheels from the supporting surface, means for automatically fastening the wheels in their raised positions, and means under the control of an operator for releasing the wheels.

70 2. In an ice sawing machine the combination with a sled structure and ice sawing mechanism carried thereby, of a motor, propelling wheels, a support for the wheels mounted for swinging movement, means for lifting the wheels under the control of an operator, means for automatically fastening the wheels in their lifted positions, means under the control of an operator for releasing the wheels, and resilient means for applying the wheels automatically when released to surface engaging position.

75 3. An ice sawing machine including a movable structure, a motor thereon, sawing mechanism carried by the structure and driven by the motor, a propelling wheel, yielding means for holding the wheel normally in engagement with a supporting surface, foot operated means for lifting the wheel, means for automatically holding the wheel in its raised position, means under the control of the operator for releasing the wheel, and reversible change speed mechanism for transmitting motion from the motor to the wheel when the wheel is in any one of its positions.

80 4. Saw cutting mechanism including a movable structure, a saw, a motor for actuating the saw, a pivoted structure, a propelling wheel carried thereby, a yielding restrained rock shaft connected to the pivoted structure for holding the wheel normally in lowered or active position, a toothed actuating member operatively connected to the shaft, lever actuated means for shifting said operating member to rock the shaft and raise the wheel, means co-operating with the toothed actuating member for holding it against movement when the wheel is raised, and a tripping lever carried by said member for disengaging the member from its holding means for releasing the wheel to active position.

85 5. An ice sawing machine including a portable structure, a hood movably connected thereto, means for raising and lowering the hood, adjustable means for limiting the downward movement of the hood, a saw mounted for rotation in and projecting below the hood, means for actuating the saw, and a flap supported in front of the saw for sliding engagement with the supporting surface for intercepting particles of ice thrown by the saw and deflecting them downwardly.

90 6. An ice sawing machine including a port-

able structure, a saw for cutting ice, an arm foldable against the side of the structure, yielding means for holding the arm depressed, a blade adjustable on the arm for riding in a cut produced by the saw, and means for holding the arm against folding relative to the structure, and means for raising the arm and blade against the action of said yielding means.

- 10 7. An ice sawing machine including a portable structure, a saw, a rod slidably and rotatably mounted on said structure, a spring for holding the rod depressed, an arm radiating therefrom, a blade on the arm adapted to travel in a saw cut, and means for raising the rod and arm against the action of the spring.

8. An ice sawing machine including a supporting structure, ice sawing mechanism carried thereby, toothed propelling wheels, yielding means for holding the wheels normally in engagement with a supporting surface, means for disengaging said wheels from the supporting surface, means for automatically fastening the wheels in their disengaged positions, and means under the control of an operator for releasing the wheels.

9. An ice sawing machine including a supporting structure, a hood pivotally mounted in the front end of said structure, a saw mounted for rotation within and projecting below the hood, said saw being movable with the hood, means under the control of an operator and connected to the hood for raising and lowering the hood and saw relative to the supporting structure, means adjustable angularly relative to the hood and movable therewith for engaging the surface to be cut at a point in advance of the saw and hood thereby to limit the movement of the saw into said surface, and means supported between the surface engaging means in advance of the saw for deflecting downwardly particles thrown forwardly by the saw while cutting.

- 45 10. An ice sawing machine including a supporting structure, means for propelling it, arms pivotally mounted within the front portion of the structure and projecting therebeyond, a hood secured to and disposed between the arms for movement therewith, means for raising and lowering the hood and arms relative to the structure, a circular saw journaled in the hood, spaced strips pivotally connected to the hood and extending downwardly and forwardly relative thereto, arcuate arms integral with the strips and adjustably connected to the hood carrying arms, said strips constituting gauges for slidably engaging the surface to be cut, and a flap pivotally mounted between the arms of the supporting structure and extending between the arms of the gauge strips for slidably engaging the surface to be cut at a point in advance of the saw.

65 In testimony that we claim the foregoing

as our own, we have hereto affixed our signatures.
